CONTAINER

Morton B. Jameson, St. Paul, Minn., assignor to
 Waldorf Paper Products Company, St. Paul,
 Minn., a corporation of Minnesota

Application June 7, 1946, Serial No. 675,215

4 Claims. (Cl. 206—52)

1

My invention relates to an improvement in container and deals more particularly with a type of container used for the shipment of tubular rolls of paper or the like.

Advertising and display matter, calendars and pictures are usually mailed or shipped in rolled tubular form. For shipping purposes such rolls of paper are often placed in mailing tubes. If the roll is allowed to expand to tightly fit against the inner walls of the mailing tube, it is often difficult to remove. On the other hand if the roll is loose in the tube it can move from one end to the other so that the ends of the roll often are damaged during shipment.

It is the object of the present invention to provide a container for holding a tubular roll of paper or similar material and to hold the roll from movement longitudinally during the shipping operation. In order to accomplish this result I provide tapered or wedge shaped ends on the container which engage the ends of the roll. The tubular roll is accordingly flattened into oval or generally rectangular shape by the wedge shaped container ends which results in no permanent deformation of the paper. At the same time the wedge shape of the ends acts to hold the roll from movement during shipment, thus preventing injury to the ends of the roll.

A feature of the present invention lies in providing a container having a rectangular body which is somewhat shorter in length than the roll contained therein, and to provide wedge shaped or tapered ends on the body which deform the roll at the ends and prevent the roll from moving during the shipping operation.

A feature of the present invention resides in providing a container of rectangular cross section for containing rolls of paper or similar material so that the containers may be stacked during shipment. At the same time, however, means are provided for preventing the roll from moving endwise during shipment or transportation.

These and other objects and novel features of my invention will be more clearly and fully set forth in the following specification and claims.

In the drawings forming a part of my specification:

Figure 1 is a perspective view of my container showing the construction thereof.

Figure 2 is a diagrammatic view of the container blank from which the container is formed.

Figure 3 is a longitudinal section through the container end showing a roll of paper or the like contained therein.

2

Figure 4 is a sectional view transversely through the container, the position of the section being indicated by the line 4—4 of Figure 3.

Figure 5 is a sectional view through the container adjacent one end of the roll, the position of the section being indicated by the line 5—5 of Figure 3.

As best seen in Figure 2 of the drawings the container A includes four side wall panels 10, 11, 12, and 13, connected along parallel fold lines 14, 15, and 16. The fold line 14 separates the panels 10 and 11; the fold line 15 is provided between panels 11 and 12; and the fold line 16 is interposed between the panels 12 and 13. All of the fold lines 14, 15, and 16 are of substantially equal length.

The panels 10 and 12 are generally rectangular in outline shape, the panel 10 being connected along the fold line 17 to an end panel 19. The panel 19 is connected along a fold line 20 to the flap 21. The opposite end of the panel 10 is connected along the fold line 22 to an end panel 23. The end panel 23 is in turn connected by the fold line 24 to the flap 25. The fold lines 17, 20, 22, and 24 are generally parallel.

The panel 12 is connected at one end by a fold line 26 to an end panel 27. The end panel 27 is connected along the fold line 29 to the flap 30. At the other end of panel 12, this panel is connected by a fold line 31 to the end panel 32. The end panel 32 is connected by fold line 33 to the end flap 34. The fold lines 26 and 29 are preferably aligned with the fold lines 17 and 20 and similarly the fold lines 31 and 33 are substantially aligned with the fold lines 22 and 24.

The panel 11 is tapered or pointed on either end thereof. One end of the panel 11 is defined by a pair of converging fold lines 35 and 36 which connect this end of the panel 11 to a pair of substantially triangular flaps 37 and 39, respectively. The flaps 37 and 39 are connected along oppositely diverging fold lines 40 and 41 to the flaps 42 and 43, respectively. The outer opposed edges of the flaps 37 and 39 are substantially parallel to the other sides of these triangular flaps, being defined by fold lines 35 and 40 and fold lines 36 and 41. A slot 44 is provided between the flaps 42 and 43.

A similar structure is provided at the opposite end of panel 11. This end of panel 11 is connected by the converging fold lines 45 and 46 to substantially triangular flaps 47 and 49. The flaps 47 and 49 are connected along diverging fold lines 50 and 51 to flaps 52 and 53, respec-

tively. A slot 54 separates the flaps 52 and 53.

The panel 13 is provided with an end structure similar to that described in conjunction with the panel 11. One end of the panel 13 is connected by converging fold lines 55 and 56 to substantially triangular flaps 57 and 59. These flaps 57 and 59 are connected by oppositely diverging fold lines 60 and 61 to flaps 62 and 63. A slot 64 is provided between the flaps 62 and 63.

The other end of the panel 13 is connected along converging fold lines 65 and 66 to substantially triangular flaps 67 and 69. These flaps are connected along oppositely diverging fold lines 70 and 71 to flaps 72 and 73, respectively. A slot 74 is provided between the flaps 72 and 73.

In the assembly of my container the side wall panels are folded into tubular relation and a strip of tape 75 may be provided to hold the side walls in tubular relationship. Alternatively the panels 10 and 13 could be connected by an anchoring flange on one side of one of these panels to overlap the other panel.

After the container A has been secured in tubular form, one end thereof is preferably closed. This is done by drawing the flaps 25 and 34 into surface contacting relation, the end panels 23 and 32 then form a wedge shaped end on the container. These flaps 23 and 32 are positioned between the ends of the panels 11 and 13.

The flaps 47 and 49 are next folded up to overlie portions of the panels 23 and 32 and the triangular flaps 67 and 69 are folded downwardly overlying parts of these same panels. Simultaneously the flaps 52 and 73 overlie the flap 25 in surface contacting relation and the flaps 53 and 72 overlie the end flap 34 in surface contacting relation. Staples such as 76 are then inserted through the flaps 25 and 34 and the other flaps overlying the same to hold this end of the container closed.

The roll B of paper or similar material may next be inserted into the carton until the first inserted end is compressed between the slanting end panels 23 and 32 of the closed end. As will be noted in Figure 3 of the drawings the roll B is preferably of somewhat greater length than the panels 10 and 12 so as to necessitate compression of the ends of the roll. This compression tends to flatten out the roll into oval shape or into the generally rectangular shape illustrated in Figure 5 of the drawings. This figure shows the end of the roll when compressed within the container. Care is taken to properly proportion the container relative to the length of the roll so that the roll will not be compressed excessively. In other words, the inside periphery of the container at the roll end is sufficiently greater than the circumference of the roll to prevent buckling of the paper. Furthermore the circumference of the roll is sufficiently smaller than the inner dimensions of the carton at the roll end to prevent the roll from being bent at too sharp an angle in the compressing action.

After the roll B has been inserted in the container the remaining end thereof is closed. This

is done by drawing the end panels 19 and 27 between the ends of the panels 11 and 13 to bring the flaps 21 and 30 into surface contacting relation. The panel 11 is then folded along the fold lines 35 and 36 so that the triangular flaps 37 and 39 overlie portions of the end panels 19 and 27 and so that the flaps 42, 43, 62, and 63 overlie their adjacent end flaps. Staples 77 may then be inserted through the end flaps so as to close the container.

When the roll is thus enclosed it may be shipped considerable distances without injury to the contents. The roll B is held from movement within the container and the ends of the roll are held from injury by compressive action.

In accordance with the patent statutes, I have described the principles of construction and operation of my tubular container and while I have endeavored to set forth the best embodiment thereof, I desire to have it understood that obvious changes may be made within the scope of the following claims without departing from the spirit of my invention.

I claim:

1. In combination with a hollow compressible tubular roll, a container comprising an elongated body rectangular in cross section and of inner dimensions approximately equal to the diameter of the roll, and wedge shaped ends on said body, said wedge shaped ends compressing the ends of said roll into generally rectangular form.

2. In combination with a tubular roll of flexible material, an elongated container enclosing said roll, and wedge shaped ends on said container for compressing the ends of the roll into generally rectangular form.

3. In combination with a hollow cylindrical roll of flexible material, a tubular container rectangular in cross section and having inner dimensions substantially equal to the outer dimensions of the roll, and pointed ends on said container, said roll extending into said pointed ends and being flexed into elongated cross section thereby.

4. In combination with a hollow cylindrical tubular roll of flexible material, a tubular container substantially rectangular in cross section, and tapered ends on said container, said roll being of a length to extend into said tapered ends and to be compressed out of cylindrical cross section thereby.

MORTON B. JAMESON.
